UNITED STATES PATENT OFFICE.

EFFIE S. COLEMAN, OF BIRMINGHAM, ALABAMA.

CORSET CONFINER.

Application filed July 2, 1925. Serial No. 41,121.

To all whom it may concern:

Be it known that I, EFFIE S. COLEMAN, a citizen of the United States, residing at Birmingham, in the county of Jefferson and 5 State of Alabama, have invented certain new and useful Improvements in a Corset Confiner, of which the following is a specification.

This invention relates to improvements 10 in abdominal supports and has for its principal object to provide an attachment for a corset for drawing the front or abdominal part of the corset against the body for the purpose of causing it to fit more 15 snugly and to follow closely the contour of the figure of the body.

Another important object of the invention is to provide a corset confiner of the above 20 mentioned character which will prevent the outward bulging of the upper portion of the front of the corset, means being further provided for maintaining the confiner in proper position across the front of the top portion of the corset.

25 A further object is to provide a corset confiner of the above mentioned character which will in no way interfere with the fastening or unfastening of the corset, the confiner itself being adapted to be readily 30 detached at one end in order to permit the unfastening and removal of the corset.

35 A further object is to provide a corset confiner of the above mentioned character which is simple in construction, inexpensive, and furthermore adapted to the purposes for which the same is designated.

Other objects and advantages of this invention will become apparent during the course of the following description.

40 In the accompanying drawings forming part of this specification, and in which like numerals are employed to designate like parts throughout the same:

Figure 1 is a perspective view of a corset 45 provided with my improved confiner, the latter being shown in its inoperative position and detached at one end.

Fig. 2 is a similar view showing the position of the confiner when in use.

50 Fig. 3 is an enlarged elevational view of the elastic band comprising the present confiner, showing the manner in which the same is attached to the corset.

55 Fig. 4 is a side elevation of a corset with the elastic band unbuckled showing the nor-

mal position of the upper front portion of the corset.

Fig. 5 is a front elevation of the confiner as associated with another type of corset wherein the front of the corset has its upper 60 portion rounded extending slightly upwardly, and

Fig. 6 is a side elevation of the confiner associated with the type of corset illustrated in Fig. 5.

In the drawing wherein for the purpose of illustration is shown the preferred embodiment of my invention, the numeral 1 designates generally a corset of any well known construction, the front thereof being 70 provided with the usual fastening means for securing the free ends of the corset together when the abdominal support is worn. My improved confiner which is adapted to be attached to the corset comprises an elastic band 2 which is stitched or otherwise fastened at one end to the side portion of the corset adjacent the upper edge thereof as illustrated at 3. This elastic band is adapted to extend across the front 80 of the corset adjacent the upper edge 4 thereof and the free end of the band carries thereon the hook 5. This hook is adapted for detachable engagement with a suitable eye 6, the latter being secured to the opposite side portion of the corset adjacent the upper edge thereof as at 7. An adjusting member 8 is associated with the elastic band 2 for lengthening or shortening the same whenever necessary.

90 Suitable hooks are secured to the inner side of the front portion of the corset, the hooks being adapted to extend over the upper edge 4 of the corset and engage the upper edge of the elastic band 2 when the same 95 extends across the front of the corset and has its hook 5 in engagement with the eye 6. This is clearly illustrated in Fig. 2 of the drawing and the purpose of causing the hooks 9, any number of which may be provided as is desired, is to provide a means for preventing the elastic band from working upwardly on the corset and thus maintaining the elastic band in proper position across the front of the corset. These hooks 100 are of such a nature as to permit the elastic band 2 to be readily disengaged therefrom when the hook 5 is detached from the eye 6.

110 In Figure 4 of the drawings, the corset is shown in its normal position with the elastic

band unbuckled, and when in this position, the upper front portion of the corset bulges outwardly, and the corset does not fit the body snugly. By extending the elastic strap 5 or band 2 across the front of the corset and attaching the hook to the eye 6, the upper front portion of the corset is caused to fit more snugly and follow closely the contour of the figure of the body and thus avoiding 10 the increased prominence of the abdomen.

In Figs. 5 and 6 of the drawings, the confiner is shown as associated with another type of corset wherein the upper edge of the front portion of the corset is rounded 15 and extends above the major portion of the upper edge of the corset. With this type of corset, the elastic band 2 extends across the front but does not have its upper edge flush with the upper edge of the front portion of 20 the corset as in the case of a type of corset heretofore described. However the type of corset shown in Figs. 5 and 6 have associated therewith the hooks 10 which engage the upper edge of the adjacent portions of 25 the elastic band so that the upward movement of the elastic band will be prevented.

A corset confiner of the above mentioned character may be readily and easily attached to any conventional type of corset and will 30 not cause any discomfort to the wearer, but will at all times be positive and efficient in carrying out the purposes for which it is designated. With the use of a corset confiner of the above mentioned character, the 35 need of having to wear a brassière, girdle,

and other abdominal supports is unnecessary. My improved corset confiner is associated with a corset in such a manner as not to interfere with the fastening or unfastening of the corset and furthermore the 40 confiner itself may be readily disengaged at one end of the corset in removing the corset.

While I have shown the preferred embodiment of my invention, it is to be understood that various changes in the size, shape and arrangement of parts may be resorted to without departing from the spirit or sacrificing any of the advantages of the appended claim. 45

Having thus described my invention, what I claim as new is:—

A corset confiner of the class described comprising an elastic band secured at one end to one side portion of a corset adjacent the upper edge thereof, said band adapted to extend across the front of the corset adjacent the upper edge, an eye secured to the opposite side portion of the corset adjacent the upper edge thereof, a hook carried by 55 the free end of the band and adapted for detachable engagement with said eye, means for adjusting the length of said elastic band, and a series of hooks secured to the front of the corset and adapted to extend over 60 the upper edge of the corset and the upper edge of the elastic band for preventing the upper movement of the latter. 65

In testimony whereof I affix my signature.

MRS. EFFIE S. COLEMAN.
